UNITED STATES PATENT OFFICE.

ALMON W. CURTIS, OF CORTLAND, NEW YORK.

TOP-PROP FOR AUTOMOBILES AND CARRIAGES.

1,201,265.

Specification of Letters Patent.

Patented Oct. 17, 1916.

Application filed April 1, 1913. Serial No. 758,145.

To all whom it may concern:

Be it known that I, ALMON W. CURTIS, of Cortland, in the county of Cortland, in the State of New York, have invented new and useful Improvements in Top-Props for Automobiles and Carriages, of which the following, taken in connection with the accompanying drawings, is a full, clear, and exact description.

- 10 This invention relates to certain improvements in top props for automobiles and carriages and refers more particularly to the means for bracing the prop sections against relative movement when assembled for use.
- 15 The main object, therefore, of my present invention is to prevent the turning of the bow supporting sections of the props upon their companion sections and also to more effectively brace the rear props where the
- 20 load and strains are most severe owing to the wind pressure on the top when the car is in motion. In other words, I have sought to provide simple means for centering and bracing the top receiving sections of the
- 25 props without adding to their weight or cost of manufacture, and at the same time to facilitate and expedite the work of assembling these parts upon the seat or body of the vehicle.
- 30 Other objects and uses relating to specific parts of my invention will be brought out in the following description.

In the drawings Figure 1 is a perspective view in dotted lines of a carriage seat equipped with my improved top props. Fig. 2 is an enlarged perspective view of one of the front props which is commonly termed a "goose-neck". Fig. 3 is an enlarged perspective view of one of the rear drop props and adjacent end of the connecting rail. Fig. 4 is an enlarged perspective view of a modified rear prop, technically known as a "solid prop". Fig. 5 is an enlarged perspective view of a front prop similar to Fig. 2, except that the seat section is slightly modified. Fig. 6 is a side elevation, partly in section, of a portion of the drop prop shown in Fig. 3. Figs. 7 and 8 are perspective views of the interlocking ends of the front prop sections shown in Fig. 1.

In order that my invention may be clearly understood, I have shown, by dotted lines, a carriage seat A— has equipped with a pair of front props —1— and an additional pair of rear props —2— having their bow-supporting sections forming the terminal ends

of a shifting rail —3— which passes around the upper edge of the back of the seat.

Each prop comprises two sections, one of which is adapted to be secured to the seat 60 and may be termed the seat section, while the other section constitutes a direct support for the bows of the top and may be termed the bow-supporting section, both props being made of steel forgings or equivalent 65 metal.

The seat section of each prop preferably consists of an eye bolt having an annular flange or shoulder —4—, an apertured head —5— and a threaded shank or bolt —6—, as 70 shown in Figs. 1 to 6 and 8, or a plurality of bolts —6'—, as shown in Fig. 5, the threaded shank or bolts being passed through suitable apertures in the side of the seat and are engaged by nuts —7— for drawing the 75 flange 4 firmly against the outer face of said seat, leaving the apertured head 5 projecting laterally some distance therefrom. The head of each eye bolt is provided with a V-shaped groove —8— extending diametrically across one side thereof parallel with the axis of the bolt. The object of this particular disposition of the groove relatively to the bolt is to permit the formation of a 80 relatively deep groove, without weakening the head or increasing its size or weight, thereby permitting the use of a V-shape rib of equal depth on the companion section to facilitate and expedite the work of assembling these parts, one upon the other, and 85 also to more effectively brace or lock the sections against relative turning when adjusted for use. Each bow-supporting section is also provided with a head —9— of substantially the same diameter as that of the apertured head —5— of the eye bolt with which it is adapted to coöperate, and is provided with a V-shape rib —10— of approximately the same form and size as the groove —8— of bolt head and is also provided with a 90 threaded shank or bolt —11— integral with and projecting from the center of the rib midway between its ends and adapted to pass through the head of the eye bolt for engagement by a suitable nut —12—, by 95 which the two parts are firmly clamped together.

It is now clear that when the seat sections are properly secured in place and the bow supporting sections placed therein, the latter 100 are self-centering and self-aligning, so that it is only necessary to apply and tighten the 105

nuts to firmly lock such sections in proper position against relative turning movement, the registering V-shape ribs and grooves serving to brace the entire top against distortion and to hold the prop sections in operative engagement in case the nuts should become temporarily loosened.

The description thus far given applies to both the front and rear props, but owing to the fact that by far the greatest load and strain is carried by the rear props, whether "drop" or "solid," the ribbed sections for the rear props are preferably connected by a brace rail —3— which follows the contour of the upper portion of the back of the seat and serves to additionally brace such sections against relative movement in their respective holders or seat sections. The end of this rail and, therefore, the ribbed sections of the rear props, may be provided with drop hangers —15—, as shown in Figs. 1 and 3, or with single lateral arms —16—, as shown in Fig. 4, but in either case the V-shape ribs of one section entering the V-shape grooves of the other section positively locks said sections against relative turning and reduces the strain on the rail,

which in turn additionally braces the corresponding sections against any tendency to turn.

What I claim is:

A top prop for carriages comprising a one-piece seat-supported section and a one-piece bow-supporting section, said sections having abutting faces provided, respectively, with a single V-shaped groove and a single V-shaped rib fitting in the groove, and each extending diametrically across the sections from side to side whereby relative rotary movement of the sections is prevented, one of the sections having a threaded shank passing through an aperture in the other section between the ends of the groove and rib, and provided with a nut for drawing the rib into the groove, said rib and groove extending diametrically of the aperture.

In witness whereof I have hereunto set my hand this 28th day of March 1913.

ALMON W. CURTIS.
